CLAIM

The ornamental design for a pipe saddle with a hanger retainer, as shown and described.

DESCRIPTION

FIG. 1 is a perspective view of a pipe saddle with a hanger retainer showing our new design;

FIG. 2 is a front elevational view of the pipe saddle with a hanger retainer;

FIG. 3 is a right elevational view of the pipe saddle with a hanger retainer;

FIG. 4 is a bottom plan view of the pipe saddle with a hanger retainer;

FIG. 5 is a rear elevational view of the pipe saddle with a hanger retainer; and,

FIG. 6 is a left elevational view of the pipe saddle with a hanger retainer.

The broken lines show portions of the design that form no part of the claimed design.
